UNITED STATES PATENT OFFICE.

JAMES E. FOX, OF MINNEAPOLIS, MINNESOTA, ASSIGNOR OF ONE-HALF TO
DAVID C. LOEWENSTINE, OF SAME PLACE.

SHOW-CASE.

SPECIFICATION forming part of Letters Patent No. 354,893, dated December 28, 1886.

Application filed August 3, 1885. Serial No. 173,315. (No model.)

To all whom it may concern:

Be it known that I, JAMES E. FOX, a citizen of the United States, and a resident of Minneapolis, in the county of Hennepin, in the State of Minnesota, have invented certain new and useful Improvements in Show-Cases, of which the following specification is a full, clear, and exact description, reference being had to the accompanying drawings, in which—
Figure 1 is a side view of the case closed, and Fig. 2 is a side view of the case with cover elevated. Fig. 3 is a side view of a portion of the case, showing the relative positions of the parts of the cover-hinge when the cover is partially elevated. Figs. 4 and 5 are enlarged details of the form of peg used to support hats, caps, and similar goods in the case. Figs. 6 and 7 are enlarged details illustrating the construction of the tilting mechanism of the goods-supporting pegs. Fig. 8 is a vertical section, cutting from front to rear, of the case closed. Fig. 9 is a similar view showing the case opened and the display-frame elevated. Fig. 10 is a sectional view, looking from the front, of a portion of one side of the case, taken in a plane indicated by the line 1 1, Fig. 8. Fig. 11 is a horizontal section of the upper display-frame in a plane indicated by the line 2 2, Fig. 12. Fig. 12 is a side view of a portion of the upper display-frame. Fig. 13 is a horizontal section of one side of the middle display-frame in a plane indicated by the line 3 3, Fig. 14. Fig. 14 is a side view of the lower part of the middle display-frame. Fig. 15 is a horizontal section of one side of the lower display-frame in a plane indicated by the line 4 4, Fig. 16. Fig. 16 is a side view of the lower part of the lower display-frame. Fig. 17 is an enlarged detail view illustrating the construction of the mechanism for supporting the display-frames, the view being a vertical section of the upper corner of the rear end of the middle frame lying down, and through one of the supporting-rails of the frame. Fig. 18 is an enlarged view of a section of the case, illustrating the relative positions and the arrangement of the tracks upon which the display-frames run. Fig. 19 is an enlarged cross-sectional view of one of the display-frames with

the goods-supporting pegs turned up, and Fig. 20 is a similar view with the pegs turned down. Fig. 21 is a front view of a portion of one of the frames with the pegs turned up, as shown in Fig. 19.

This invention relates to show-cases for displaying articles of merchandise in stores, &c., more especially hats, caps, furs, and similar goods, having a series of goods-supporting frames, in which the goods are so held that when the frames are folded down in compact form within the case the goods will not fall out of the frames, but at the same time be easily accessible when the frames are turned upward, as hereinafter shown, and then specifically defined by the claims.

In the drawings, A' is the base of the case, A² A³ the sides, A⁴ the back, A⁵ the front, and A⁶ the top, of the same. The base, sides, and back are all secured to each other, while the front and top are in one piece, or formed solidly together, and adapted to lie loosely upon the front and top of the structure, as shown in Figs. 1 and 8. The top and front A⁵ A⁶ are firmly held at right angles to each other by suitable metal straps and braces at their curved end, and connections will be formed with glass panels, through which the interior of the case may be observed. The sides and the back of the case may also be formed with glass panels, if preferred.

Upon each end of the rear part of the top A⁶ a metal bracket, B', is secured, passing down outside of the sides A² A³ of the case, and pivoted at a' in a slot, a², in one end of a bar, B². The other end of the bar B² is pivoted upon the rear edge of the side, as A³, a short distance down from the top. The bracket B' is curved forward at B³, and when the cover is folded down, as shown in Fig. 1, this curved portion rests behind and partially beneath an anti-friction grooved roller, b, on the upper part of the side of the case. Only one set of these brackets and bars is shown; but each side of the case will of course be supplied with its own set. By this arrangement of the brackets and slotted bars, when the front and top of the case are raised up by the handle A⁷, the top A⁶ will slide back over the upper edge of

the back A^4 and drop down behind the back a short distance, as shown in Figs. 2 and 9, thereby occupying less room than it would if it were merely hinged to the back A^4 and also 5 lowering the front A^5 , which is then in a horizontal position, as shown in Fig. 2, so that the handle A^7 is more readily reached for again shutting the case. When the front and top are thus raised, the bars B^2 are brought into 10 an inclined position downward and backward, substantially as shown in Fig. 2. This position of the bars, brackets, and top of the case is such that the bars, under the weight of the front and top, cause the top to hug closely to 15 the back of the case, and also act as braces to prevent the front and top from tipping forward, they being thereby held securely in their raised position. At the same time a gentle pull forward and downward on the handle A^7 20 readily lowers the front and top again to their closed position. A variation of the inclination of the bars B^2 varies the stability of the support of the front and top when thus raised. If the inclination of the bars B^2 is lessened— 25 that is, if they are arranged in a position nearer horizontal—the front and top are held up with greater firmness. If the inclination is increased—that is, if they are brought nearer to a vertical position—the support of 30 the front and top is less firm. Thus I can adapt the bars B^2 to different weights of the front and top, and make their support as firm, and as firm only, as desired.

When first raised, as in Fig. 3, the tendency 35 is for the rear edge of the top A^6 to rest upon the upper rear corner of the back A^4 until the angle of elevation is sufficient to overcome the friction, when the cover and front would slip back suddenly until stopped by the pivot a' 40 striking the bottom or inner end of the slot a^2 . To avoid this sudden slipping back, I form the curved portions B^3 upon the brackets, and arrange the anti-friction grooved rollers b on the sides $A^2 A^3$, so that just as soon as the front and 45 top $A^5 A^6$ begin to rise the curved portions B^3 , running under the rollers b , begin to crowd the cover back as soon as it begins to rise, and thereby prevent any "jumping" or jarring of the movement. These friction-rollers b also 50 serve to hold the front A^5 back against the front edges of the sides $A^2 A^3$, as otherwise the front and cover would be free to work forward as far as the slots a^2 would permit. The grooved rollers b , holding against the forward edges of the 55 brackets B' , serve to hold the front and top $A^5 A^6$ from any lateral swerving, so that there is no danger of the bracing, when used on the ends of the top and front, striking or rubbing the corners of the sides $A^2 A^3$; also, the forward 60 swells of the portions B^3 under the rollers b , when the front and top are closed down, serve to prevent a direct vertical rising movement of the top A^6 out of a perfectly-closed position. Thus the rollers b perform an important part in the operation of my improved 65 hinge mechanism. This hinge thus acts as a

binder to hold the cover in position after it drops down in closing. The hinge may be adjusted to drop the front and top down any distance desired when raised.

Upon each of the inner surfaces of the sides $A^2 A^3$, near their tops, are a number of parallel tracks, $c' c^2 c^3 c^4$, the tracks $c' c^2$ being in line one above the other, the tracks c^4 lying close to the sides $A^2 A^3$, and the tracks c^3 at a point 70 midway in a perpendicular line between the tracks $c^2 c^4$, as shown in Fig. 18.

$C' C^2 C^3$ are three oblong open goods-supporting frames, each adapted to occupy, preferably, about one-third of the interior of the case, 80 as shown in Figs. 8, 9, and 10, in Figs. 8 and 10 said frames being represented as lying in a horizontal position, one above another. In this position the frames are entirely within the case, and the front and top of the said case, 85 when let down, then completely shut the frames in the case. If more or fewer than three frames are employed, each occupies its proper proportion of the space in the case.

d' is a flat bar, pivoted by one end to the upper frame, C' , and provided with a grooved roller, d^2 , adapted to run upon the track c^2 , while a similar bar, d' , is pivoted by one end at d^4 to the same frame, C' , and provided with a grooved roller, d^5 , running upon the track c' , 90 as clearly shown in Fig. 12. The central frame, C^2 , is provided with an arm, e' , similar to the arm d' , and pivoted by one end to the frame C^2 , and having a roller, e^2 , running upon the track c^3 , while another arm, e^3 , connected 100 to the arm e' by a bar, e^4 , is also provided with a roller, e^5 , running upon the same track c^3 , as clearly shown in Fig. 14. The lower frame, C^3 , is provided with a fixed arm, g' , having a roller, g^2 , running upon the track c^4 , as clearly 105 shown in Fig. 16.

Each end of each of the frames $C' C^2 C^3$ will be provided with a set of the rollers to run upon the tracks; but only one set is shown upon each frame in the drawings.

When the frames $C' C^2 C^3$ are all folded down, as shown in Fig. 8, the central frame, C^2 , rests upon the lower frame, C^3 , and the upper frame, C' , rests upon the central frame. Then when the front and top $A^5 A^6$ are raised 115 up, as shown in Fig. 2, the upper frame, C' , may be drawn out and lifted up, as in Fig. 9, (the rollers $d^2 d^5$ supporting the lower end,) and then run back against the back A^4 . This position of the frame C' brings the arm d^3 into 120 a backwardly and upwardly slanting position, so that a pin, h' , upon the frame C' will rest upon a pin, h^2 , on the arm d^3 , and thereby support the frame in an upright position, but free to be run forward upon the tracks $c' c^2$ to display the goods, and run back to make room for the other frames. Then the central frame, C^2 , may be drawn outward and turned up 125 against the frame C' .

Pivoted in the lower parts of the frames $C^2 C^3$, upon either side, are small hooked catches i , those upon the frame C^2 adapted to catch

upon the connecting-bars e^4 of the said frame C^2 , when the latter is elevated, to hold it upright, as shown in Figs. 19, 20, and 21, while the catches i upon the lower frame, C^3 , are adapted to catch upon small stops k , attached to the front edges of the sides $A^2 A^3$ for that purpose, as shown in Fig. 9. The action of the hooks on the frame C^3 is the same as that of the hooks i on the frame C^2 . By arranging the catch i upon the central frame to catch upon the cross-bar e^4 the frame is left free to be drawn forward to the front of the case to display the goods, or moved back against the frame C^2 to make room for the lower frame to be elevated. By this means, when the frames $C^2 C^3$ are elevated, the catches i will hold them elevated. When all the frames are thus raised and sustained in a vertical position, they stand one in front of another, and substantially in the same plane, as shown in Fig. 9. They also stand partly above the sides of the case, as shown in the same figure. By the construction herein represented and described about two-thirds of the height of the frames are thus brought above the sides of the case when they are raised to a vertical position. Thus they are brought up to a convenient height for examination of the goods held by the frames, and for easily reaching the same, although the case itself may be comparatively low. At the same time the front A^5 of the case is held above and out of the way of the frames, when both the case-front and the frames are raised. The top A^6 of the case then stands in a vertical position behind the frames.

m are small levers pivoted by their centers to the lower sides or bottoms of the frames $C^2 C^3$ when elevated, and adapted, when pulled by one end, to throw the lower ends of the catches i outward and disconnect the upper ends of the catches from the arms e^4 and stops k when the frames C^2 or C^3 are to be lowered down.

When used for the display of ribbons and similar goods in rolls or compact form, the frames $C^2 C^3$ will be merely provided with rods or frames for supporting the bolts of ribbons, &c., and when used for some other kinds of goods mere shelves or hooks will be sufficient; but when used for the display of hats and caps and some kinds of furs, and boots and shoes, but more especially hats and caps, I arrange in each of the frames $C^2 C^3$ a series of parallel rods, D , pivoted by their ends in the ends of the frames $C^2 C^3$, so that they can be revolved or oscillated, and have pegs $u' u'$ thereon. In the center of each frame $C^2 C^3$ are posts C^4 , through which the rods D run, and each pair of the posts in each frame are secured together at their tops by metal frames E^1 . (See Figs. 19, 20, and 21.) In each of the posts C^4 , opposite the points where the rods D pass through them, are slots, (see Figs. 6 and 7,) out through which small arms n' , attached to the rods D , run, and each set of the arms n' of each perpendicular row of rods D are connected

together at their inner ends by rods n^2 , as shown, so that all the rods of each perpendicular row may be oscillated at once by moving its connecting-rod n^2 up or down. Each pair of the posts C^4 of each frame are connected together at intervals by cross-pieces G , and held loosely upon these cross-pieces by straps or other bearings are upright rods H , connected to the rods n^2 by a strap, n^3 , playing in mortises or holes in the said rods, so as to allow a lateral movement of the rods on the strap, so that by moving the rod H up or down each of the two perpendicular rows of the rods D may be turned over toward each other, as shown in Fig. 20.

Each of the frames E^1 is formed into a handle, E^2 , by which each of the frames $C^2 C^3$ may be raised and lowered, and in each of these handles is pivoted a small lever, F^1 , connected at its inner end by a small rod, F^2 , to one of the rods H , so that by raising and lowering the levers F^1 the rods H may also be raised and lowered, and the pegs $u' u'$ on the rods D turned into a vertical or a horizontal position. Above the levers F^1 in each of the handles E^2 is pivoted another lever, F^3 , to the inner end of which a cord or wire, t , is attached and runs down to two bell-cranks, $t^2 t^3$, (shown in dotted lines in Fig. 21,) and from thence in opposite directions to the small levers m , which operate the catches. By pulling down upon the levers F^3 it will be seen the catches i will be disconnected and leave the frames $C^2 C^3$ free to be lowered down. Springs will be attached to the catches i to throw them outward, so that they will catch upon the bars e^4 and stops k automatically when the frames $C^2 C^3$ are raised up.

The pegs upon the rods may be made of any suitable form, different kinds of goods requiring different kinds of pegs; but for supporting hats, caps, &c., I use the form shown more clearly in Figs. 4 and 5, consisting of a flat plate, u' , of metal bent around the rods D and secured thereto by rivets, screws, or similar means, or, as shown in the drawings, by punching a portion of the metal into the wood. I prefer the latter method, as being cheaper, more simple, and fully as secure as any other means. In the upper ends of the metal plates a portion is cut out on three sides, and the cut-out portion bent forward, forming a lip, u^2 , which catches behind the sweat-lining of the hat when the frames are lowered, to prevent the hats slipping from the pegs when the frames are accidentally jarred.

Spring-catches x will be attached to the frames $C^2 C^3$ to catch the levers F^1 when they are thrown down, as shown in Fig. 19, to hold the levers downward and prevent the accidental displacement or swinging down of the supporting-peg u' when the frames $C^2 C^3$ are lowered. These spring-catches will be so arranged as to be easily released by the finger of the operator when it is required to turn the pegs u' down, and automatically catch and hold

the levers when the pegs are elevated. Each of the levers F' has a lug, v' , upon its upper side, the part of the lug toward the handle E' being on a curve of which the pivot of the lever is the center, and the remainder of the lug hollowed out, as shown. Each of the levers F^3 has a downwardly-projecting lug, v^3 , which nearly touches the lug v' when the levers F' are thrown up for lowering the pegs u' , as shown in Fig. 20. The levers F' are thus always free to be moved up and down; but when the levers F' are raised up, as in Fig. 20, to throw the pegs u' downward, the lugs v' will come beneath and in front of the lugs v^3 and prevent the levers F^3 from being operated. When the pegs u' are all turned up and secured in that position by locking the levers F' with the catches α , as shown in Fig. 19, the lugs v^3 are in position to move down in front of the lugs v' , thus allowing the levers F^3 to be operated for unlocking the frames $C^2 C^3$, so that they can be lowered into a horizontal position. By this means the frames C^2 or C^3 cannot be turned down until the pegs u' are raised upward to secure the hats, &c. If the frames were turned down when the pegs are turned horizontally, the hats would all fall out; but to prevent any such mishap I provide the locking-lugs $v' v^3$. With the construction above described there are two parallel sets of oppositely-placed rods, $D D$, in each frame, the pegs $u' u'$ on one set turning inward toward those on the other set of rods simultaneously. Each article—such as a hat—rests over two of the opposite pegs on their respective rods when the frame is raised to a vertical position for display, and hangs by the upper peg of the two when the frame is lowered to a horizontal position, the pegs being then horizontal. So, when the frame is raised to a vertical position, the pegs are also in a vertical position, as shown in Fig. 19, thereby preventing the hats being shaken or thrown from the rods on which they rest, especially when the frames are moved backward or forward, both pegs being then necessary to keep the hat in place. Then, when it is desired to take one or more hats from the rods for examination or sale, the rods are turned by the means above described, so as to bring the pegs into a horizontal position, as shown in Fig. 20. In that position of the pegs the hats may be taken from the rods as readily as from a shelf, and as readily replaced thereon. Having described my invention and set forth its merits, what I claim is—

1. A show-case having goods-supporting frames $C' C^2 C^3$ contained therein, and provided with a front, A^5 , and top A^6 , formed in fixed relation to each other, the top being hinged at the rear of the case to the same, the said front and top being adapted to be raised and held with the top in a vertical position and the front in a horizontal position at some distance above the case, whereby the said frames may be raised to and held in a verti-

cal position partly above the case and beneath the said front, substantially as herein specified.

2. A show-case having a bottom, back, and sides in fixed relation to each other, and provided with slotted pivoted bars B^1 , in combination with a front and top in fixed relation to each other, and provided with brackets B' , adapting the top when raised to slide back and drop down behind the back A^4 , substantially as described. 7c

3. A show-case having a bottom, back, and sides in fixed relation to each other, and provided with slotted pivoted bars B^2 , and anti-friction grooved rollers b , in combination with the front and top in fixed relation to each other, and provided with brackets B' , having curved portions B^3 , substantially as and for the purpose herein specified. 8c

4. The combination, in a show-case, of a case bottom, sides, and back, $A' A^2 A^3 A^4$, tracks $c' c^2 c^3 c^4$, and goods supporting frames $C' C^2 C^3$, provided with rollers adapted to run upon the said tracks, arranged and operating substantially as herein shown and described. 9c

5. In a show-case, a series of goods-supporting frames or holders contained within the case in a horizontal position one above another, and adapted to be raised to and independently sustained in a vertical position one in front of another and substantially on the same plane without removal from the case, for the purpose herein specified. 95

6. In a show-case, a series of goods-supporting frames or holders contained within the case in a horizontal position one above another, and adapted to be raised to and sustained in a vertical position one in front of another on substantially the same plane, each frame being partially above the sides of the case, in combination with a case having a connected front and top adapted to be raised and held away from the said frames, substantially as and for the purpose herein specified. 10c

7. In a show-case, a goods-supporting frame adapted to be placed and held in both a horizontal and a vertical position and provided with two sets of oppositely-located rods, $D D$, the respective sets of rods having pegs $u' u'$, adapted to be turned inward simultaneously toward each other and upward parallel with each other, substantially as herein specified, whereby each article is adapted to be held by two opposite pegs on opposite rods of the frame, the pegs being adapted to be thus turned inward toward each other to permit the full removal of the article, substantially as herein set forth. 115

8. The combination, in a show-case, of a frame having pivoted rods D and pegs u' , the connecting arms n' , rods n^2 , handle E' , lever F' , having a lug, v' , lever F^3 , having a lug, v^3 , catch i , lever m , and connecting cord or wire t , substantially as shown and described. 125

9. In a show-case, a holding-peg, u' , formed of a flat plate of metal bent at one end around

a rod, D, and held in place thereon by a portion of the metal cut in and bent from the plate into the rod, and having at the other end a lip, u^2 , cut in and bent outward from the plate, in combination with the arms n' and n^2 , straps n^3 , and rod H, substantially as herein specified.

In testimony whereof I have hereunto set my hand in the presence of two subscribing witnesses.
